UNITED STATES PATENT OFFICE.

STEPHEN D. TUCKER, OF NEW YORK, N. Y.

SHEET-DELIVERY APPARATUS FOR CYLINDER PRINTING-MACHINES.

SPECIFICATION forming part of Letters Patent No. 365,952, dated July 5, 1887.

Application filed July 9, 1886. Serial No. 207,537. (No model.)

To all whom it may concern:

Be it known that I, STEPHEN D. TUCKER, a citizen of the United States, residing at New York, county of New York, and State of New York, have invented certain new and useful Improvements in Sheet-Delivery Apparatus for Cylinder Printing - Machines, fully described and represented in the following specification and the accompanying drawings, forming a part of the same.

This invention relates particularly to the rotating delivery carrier or cylinder of a cylinder printing-press—that is to say, the carrier which operates to take the sheets from the impression-cylinder and deliver them to the fly or other similar piling device, by which they are piled one upon another upon the piling-table.

It is the object of the invention to provide means by which the ink upon the freshly-printed sheet will be prevented from coming into contact with the surface of the rotating carrier and thereby offsetting, so as to soil and injure the sheets.

As a full understanding of the invention can be best given by a detailed description of the mechanism in which it is embodied, all preliminary description of the invention will be omitted and a detailed description given, reference being had to the accompanying drawings, in which—

Figure 1 is a partial side elevation of an ordinary form of carrier printing-press provided with a delivery-cylinder constructed according to the present invention, only so much of the press being shown as is necessary to illustrate the application of the improvements. Fig. 2 is an end elevation of the same, looking from the left of Fig. 1. Figs. 3, 4, 5, and 6 are views, upon an enlarged scale, illustrating the construction of the delivery-carrier; and Figs. 7 and 8 are views, upon a still larger scale, illustrating a modification, which will be hereinafter referred to.

Referring particularly to Figs. 1 and 2, it is to be understood that A represents a portion of the frame-work, B the bed, C the form, D the impression-carrier, E the feed board or table, F the delivery-cylinder, and G the fly, of an ordinary form of cylinder printing-press. The bed B is provided with any of the ordinary forms of connection, (not shown,) by

which it is reciprocated back and forth beneath the cylinder D, and the cylinder D is provided with any suitable means, (also not shown,) by which it is revolved in the direction indicated by the arrow, so as to move in unison with the bed while the impression is being taken, as is common. The cylinder D is also provided with the usual sheet-grippers, (not shown,) for taking and holding the sheet during the printing. The feed-board E is arranged in the usual position above and at one side of the impression-cylinder, and the fly F is arranged beneath the outer end of the feed-board in the usual position and is provided with the usual devices (not shown) by which it is vibrated at the proper times to receive and deposit the sheets upon the piling-table.

The delivery-carrier F, which may consist of a continuous roll or drum, but will preferably be composed of a number of rings or pulleys, as is shown in the present case, is located at the side of and in close proximity to the impression-cylinder and in such position as to be between the impression-cylinder and the upper end of the fly when the latter is in its raised position. The delivery-carrier is driven in unison with the impression-cylinder in any suitable manner, as by the gears 49 50, and 85 is provided with ordinary sheet-grippers, which are operated at the proper times to take the sheets from the impression-cylinder, transfer them to the delivery-carrier, and then deliver them onto the fly to be piled. It will readily be seen that, with the mechanism thus organized, when each sheet is transferred from the impression-cylinder to the delivery-carrier its last or freshly-printed side is brought next to the surface of the delivery-carrier, thereby frequently causing the ink from the freshly-printed sheet to offset onto the surface of the carrier to such an extent as to soil the sheets.

It is the especial object of the present invention to obviate this difficulty; and to accomplish this result those pulleys or portions of the carrier which underlie the printed portions of the sheet are slightly depressed and are provided with fine points or projections 103 which operate to sustain the sheet and prevent its freshly-printed surface from coming into contact with the surface of the carrier.

The construction of the delivery-carrier will

now be more particularly described. This carrier, as stated, consists in the present case of a number of pulleys, which are mounted upon a shaft, 48. The end or outside pulleys, 47, are connected by a bar, 46, which serves as a seat for the grippers 10 to close against to grasp the leading end of the sheet. These two pulleys are also provided with bearings for the gripper-shaft 12. Located just inside 10 of the pulleys 47 are a pair of pulleys, 45, which are of the same size as the pulleys 47, and are so adjusted as to lie just beneath the blank side margins of the sheets.

Between the pulleys 45 are arranged a number 15 of pulleys, 44, which are slightly smaller than the pulleys 45, 47, and are provided around their peripheries with fine points or projections 9, which are of sufficient length and are sufficiently numerous to sustain the sheets and 20 prevent them from coming into contact with the surfaces of the pulleys. The points 9 may be rigid studs or pins, as shown in Figs. 2, 5, and 6; or they may, if preferred, be formed by freely-turning or fixed star-like wheels or disks, 25 which wheels or disks may be arranged to turn on studs projecting from the sides of the pulleys 44, as shown in Fig. 7 and 8; or they may be arranged in slots in the peripheries of the pulleys.

30 The grippers 10 may be operated in any suitable or convenient manner. As shown in the present instance, the gripper-shaft 12 is provided with an arm, 13, which is acted on to close the grippers by a spring, 14, which is arranged in the usual or substantially the usual manner. The opening of the grippers to release the sheets is effected by means of a stationary cam, 15, which engages with a stud or bowl, 8, on the arm 13 of the gripper- 35 shaft, while the opening of the grippers preparatory to taking the sheets is effected by means of a rocking cam, 16, which is moved by an arm, 17, which is acted on by a cam, 18, on the shaft of the impression-cylinder.

45 In order to insure the sheets being carried around by the delivery-carrier after their leading ends have been released by the grippers of the delivery-cylinder, and also to prevent the sheets from being drawn off the delivery-carrier by their own weight and falling suddenly down in front of the fly, there may and preferably will be provided a pair of light disk-like rolls, 43, which rest with their weight upon the pulleys 45, and thus grasp the margins of the sheets and carry them forward and prevent them from being drawn off the carrier prematurely. The pulleys 45, and also, if desired, the pulleys 44, may be made in two parts, as shown in Fig. 4, so that they can be 55 shifted to different positions on the shaft 48, to conform to the width of the sheet being printed, and the disks 43 will be made adjustable laterally on their shaft 42 to correspond.

The operation of the improved delivery-carrier, in connection with the other parts, is 65 as follows: The sheets will be taken by the

grippers of the impression-cylinder and presented to the form and printed in the usual manner. After being printed, they will, at the proper time, be released by the grippers 70 of the impression-cylinder, and as they are thus released their leading ends will be taken by the grippers 10 and clamped onto the bar 46, and transferred onto the delivery-carrier. As the sheets are thus transferred onto the 75 delivery-carrier, their blank margins will overlie and rest upon the pulleys 45, while their freshly-printed portions, which overlie the pulleys 44, will be sustained and held out of contact with the pulleys by the points 9, and 80 thus the fresh ink will be prevented from offsetting. As the leading ends of the sheets arrive above the upper end of the fly, they will be released by the grippers 10, and, as the ends of the fly-fingers extend inward between 85 the pulleys of the delivery-carrier, the sheets will be directed off the carrier and will pass downward in front of the fly and be piled.

If in any case the fly-fingers should smut the sheet by coming into contact with the freshly-printed surface, this may be avoided by providing the fly-fingers with the star-wheels 19, as shown in Fig. 5.

Although, as before stated, it is preferable to make the delivery-carrier of a number of 95 pulleys, as shown, it is not necessary to do so. It may be a continuous drum or cylinder, such parts of its surface as underlie the printed part of the sheet being provided with the points 9, either in the rigid form or in the 100 form of the star-wheels set into the cylinder.

What I claim is—

1. The delivery-carrier F, provided with points 9, for holding the sheets out of contact with its surface, and provided with the adjustable pulleys 45, having smooth peripheries and arranged to underlie the margins of the sheets, substantially as described.

2. A delivery-carrier composed in part of rings or pulleys having points on their peripheries and in part of rings or pulleys having smooth peripheries, substantially as described.

3. The delivery-carrier F, composed in part of pulleys provided with the points 9, for holding the sheets out of contact with its surface, and in part of pulleys having smooth peripheries, in combination with the coating feeding-pulleys 43, substantially as described.

4. A delivery-carrier composed in part of rings or pulleys having points on their peripheries, and in part of rings or pulleys having smooth peripheries, some or all of said rings or pulleys being made in parts so as to be adjustable with relation to each other, substantially as described.

In testimony whereof I have hereunto set my hand in the presence of two subscribing witnesses.

STEPHEN D. TUCKER.
